UNITED STATES PATENT OFFICE

149,373

DESIGN FOR A LACE MEDALLION

Reinhard A. Paessler, West New York, N. J.
Application July 18, 1947, Serial No. 140,362

Term of patent 7 years

(Cl. D3—9)

To all whom it may concern:

Be it known that I, Reinhard A. Paessler, a citizen of the United States, residing at West New York, in the county of Hudson and State of New Jersey, have invented a new, original, and ornamental Design for a Lace Medallion, of which the following is a specification, reference being had to the accompanying drawing, forming part thereof.

The figure is a plan view of a lace medallion showing my new design, and illustrating the same against a black background in order to emphasize the details thereof.

I claim:

The ornamental design for a lace medallion, as shown and described.

REINHARD A. PAESSLER.
